UNITED STATES PATENT OFFICE.

EDWARD M. HEWLETT AND CHARLES C. BADEAU, OF SCHENECTADY, NEW YORK, ASSIGNORS TO THE GENERAL ELECTRIC COMPANY, A CORPORATION OF NEW YORK.

LAMINATED-LEVER SWITCH.

SPECIFICATION forming part of Letters Patent No. 728,231, dated May 19, 1903.

Application filed December 16, 1898. Serial No. 699,438. (No model.)

To all whom it may concern:

Be it known that we, EDWARD M. HEWLETT and CHARLES C. BADEAU, citizens of the United States, residing at Schenectady, county of Schenectady, in the State of New York, have invented certain new and useful Improvements in Laminated-Lever Switches, (Case No. 862,) of which the following is a specification:

- 10 Our present invention relates to switches for electric circuits, particularly to those intended to carry large currents, and which are therefore of considerable weight and size. In switches for this service it has heretofore been
- 15 customary to make the stationary terminals with some degree of flexibility, so that they would make a firm rubbing contact with the large and heavy solid blade of the switch. If the fixed terminals are small enough to get
- 20 the required spring, they are not sufficiently heavy to carry the required current. If made large, they are too stiff. In our invention we provide for the switches fixed terminals of ample size for the designed current. These
- 25 are rigid, or substantially so. The switch-blades, however, are laminated and make side-bearing sliding or rubbing contact with the fixed terminals. In order to avoid the difficulty of pivoting the laminated blades,
- 30 we attach them to a rigid bar pivoted at one end to a fixed terminal of the switch, the blades being attached near the middle, so that each end is free. By this construction the blades and terminals may be as large and
- 35 thick as is desirable or necessary, making good contact and carrying the rated load without undue heating.

The drawings annexed show our invention as applied to a three-pole switch, though of course other kinds might be similarly made.

In the drawings, Figure 1 is a front elevation, and Fig. 2 a side elevation, of the switch.

In both the figures, A is the usual base or "board" for the switch, of slate or other suitable insulating material.

B is the switch-handle, attached to a bar B', of insulating material, joining the three bars F F F, which carry the switch-blades. A description of one of these suffices for all, 50 as the three are similar.

To the bar F is affixed a cross-piece F'. Upon each end of the cross-piece is a plate f', shaped to conform to the curves of the laminated blades D, the latter being secured in place by a strip F², screws passing through 55 the strip into the cross-piece F'. The laminated blade, it will be observed, is free at each end and makes side-bearing rubbing contact upon the fixed terminals C C, &c. In the illustrated construction the blade D always makes contact at one end with the terminal to which the bar F is pivoted. At its other end the blade is slotted at d, so that it may readily pass over the fixed terminals C-C. The blade may be composed of as many 60 sheets of copper or other conducting material as may be desired, and it is manifest that increased current-carrying capacity may be obtained to almost any desired extent by simply increasing the size of the switch. 65 A part of the outer end of the bar F is formed on an arc struck from the center, on which the bar swings. Spring-terminals E E' make or break the circuit as the switch is closed and opened upon contacts f, located on this 70 part of the blade, these supplemental contacts being designed to break contact in opening the switch a little later than the bridge contacts, and thereby serving to take the arc 75 and prevent injury to the bridging contacts. 80 They may be shod, if desired, with carbon blocks, thus increasing their cheapness and durability and preventing spattering of metal when the circuit is opened. In the illustrated construction the center terminal E' is made 85 a little longer than the others, so that this blade of the switch will make contact before the other two. In the particular switch here shown it is so arranged in order to connect the equalizer (in a plant employing a number 90 of compound-wound dynamos) before the positive and negative terminals of the generator are connected to the bus-bars. One end of each terminal is threaded, as shown at C², and the terminals are secured to the switch-board by nuts C' in the usual way.

By the construction here outlined we are enabled to make a switch which will carry large currents without undue heating and will always make good contact between the 100

blade and the fixed terminals. At the same time, if desired, only one kind of switch of this general type need be manufactured, changed only in size to adapt it to all ordinary requirements.

What we claim as new, and desire to secure by Letters Patent of the United States, is—

1. A switch for heavy currents, having fixed terminals, a pivoted blade or bar entering and engaging the jaws of said terminals, and laminated bridging contacts carried by said bar making rubbing side contact on the outer faces of the fixed terminals.

2. A switch for heavy currents, having fixed terminals, flexible blades making side contact with the fixed terminals, a pivoted bar to which the blades are fixed, and supplementary terminals making and breaking contact upon the bar.

3. The combination, in a switch, of a pair of slotted fixed terminals, a bar pivoted in one of the slotted terminals and entering the

slot in another when the switch is closed, bridging contacts with free ends each making rubbing side contact with a fixed terminal, and supplementary terminals making and breaking circuit on the bar.

4. The combination, in a switch, of a pair of slotted fixed terminals, a bar pivoted in one of the slotted terminals and entering the slot in another when the switch is closed, a pair of flexible bridging contacts attached to the bar and having free ends, each of which makes rubbing side contact with a fixed terminal, and supplementary spring - contacts attached to the fixed terminals making and breaking circuit on the bar.

In testimony whereof we have hereunto set our hands this 14th day of December, 1898.

EDWARD M. HEWLETT.
CHARLES C. BADEAU.
